WILLIAM F. HUTCHINSON, OF BOUND BROOK, NEW JERSEY, ASSIGNOR TO
THE ATLAS MATCH COMPANY, OF JERSEY CITY, NEW JERSEY.

MATCH-MACHINE.

SPECIFICATION forming part of Letters Patent No. 664,642, dated December 25, 1900.

Application filed August 23, 1900. Serial No. 27,762. (No model.)

To all whom it may concern:

Be it known that I, WILLIAM F. HUTCHINSON, of Bound Brook, Somerset county, New Jersey, have invented certain new and useful 5 Improvements in Match-Machines, of which the following is a full, clear, and exact description.

My invention relates to improvements in match-machines.

One object of my invention is to produce a machine which cuts match-splints without waste, which is adapted to deliver the splints rapidly and uniformly into an ordinary match holding or dipping frame, which has automatic 15 means for fastening the splints in place, and also to produce a guide-plate which will hold, guide, and separate splints so that they will be spaced correctly in the dipping-frames, and, further, to make this guide-plate a heating- 20 plate also, which will not only thoroughly heat or char the match ends, but will also encompass and quickly heat and dry the greater portion of each match-splint.

Another object of my invention is to make 25 a machine of this character which is very positive in operation and adapted to work continuously without great care on the part of the operator.

To these ends my invention consists of a 30 match-machine the construction and arrangement of which will be hereinafter fully described and claimed.

Reference is to be had to the accompanying drawings, forming part of this specification, 35 in which similar figures of reference refer to similar parts throughout the several views.

Figure 1 is a plan view of the machine embodying my invention. Fig. 1^a is a detail sectional plan of a part of the cutters, illustrating the manner in which the alternate 40 splints are spread or forced in opposite directions as they are cut. Fig. 2 is a cross-section of the same. Fig. 3 is a broken detail plan of the inner end guide-plate, showing the manner in which the splints are delivered into the 45 grooves of the plate. Fig. 4 is a broken side elevation of a portion of the machine, showing particularly the means for feeding the dipping-frames through the machine and the 50 means for working the plunger which pushes

the stock into the cutters. Fig. 5 is a detail cross-section through the cutters and shows the mechanism for guiding the splints and for preventing them from following the cutters in their rotation. Fig. 6 is a detail side elevation of one of the cutters and the splint guiding or ejecting device; and Fig. 7 is a broken detail perspective view showing the means for tightening the slats of the dipping-frame, so that they will clamp the match- 55 splints between them.

The machine is provided with rotary cutters 10, which are of a well-known type and need no detailed description, the cutters being spaced apart the width of a match-splint 60 and the edges of one set of cutters overlapping those of the other set, as shown best in Fig. 5, and this arrangement causes a strip of veneer or stock when fed transversely downward between the cutters to be cut into a series of splints, as hereinafter described and as well understood. The cutters 10 are carried by transverse shafts 11, which at one end are geared together by gears 12, so that they will rotate oppositely and in unison, while 65 one gear 12 is driven by an idler 13, which in turn is driven by the gear 14 on the main driving-shaft 15, this being driven by a pulley 16 or equivalent driving device. The above apparatus is suitably mounted on a supporting- 70 frame 17 and no novelty whatever is claimed for it. Above the cutters 10 is a suitable hopper 18, which is supported, as shown, on cross-rods 18^a, and this carries the stock 19, which, as illustrated, represents strips of veneer each the thickness of a match-splint and of a width corresponding to the length of a splint. I wish it understood, however, that the means illustrated for supplying veneer to the cutters is not particularly new, and I do 75 not confine myself to this means, as my invention relates chiefly to the mechanism for receiving, guiding, clamping, and heating the splints after they are cut. As shown, the stock 19 is pressed forward by a spring 20, 80 though a weight or other means may be substituted, and the strips 19 are adapted to be pushed downward one by one through the slot 21 (see Fig. 5) in the bottom of the hopper 18, 85 and as soon as the lower edge of the strip 90

reaches the cutters 10 it is seized by them and quickly carried downward and severed into splints.

The strips 19 are pushed downward by a plunger 22, (see Fig. 2,) which reciprocates vertically and is carried by the cross-rod 23, which connects by means of pitmen 24 with the eccentric-straps 25, the latter being held on the faces of the eccentrics 26, which are secured to one of the shafts 11, as shown best in Figs. 1 and 7. It will thus be seen that the plunger 22, actuated by the eccentrics, will have a constant and regular up-and-down movement, and when a strip 19 is pushed down and the plunger 22 rises the spring 20 forces the strips 19 forward, so that another comes to position beneath the plunger and above the slot 21.

When a strip of veneer has been cut by rotary cutters like the kind shown, the tendency is for the splints to stick between the cutters and to be carried around with them, the splints sticking alternately to the two sets of cutters—that is, one splint will stick to the left-hand cutter, the next to the right-hand cutter, and so on. The reason for this separation of the splints, so that one is forced in one direction, the next in the opposite direction, &c., is probably that cutters of this class are generally made as shown in Fig. 1^a, in which a pair of knives enters between two opposite knives, the several knives of the cutters overlapping in pairs, as the drawings clearly show, and so the splints are made slightly wedge-shaped and naturally are pressed to one side. This construction is common to cutters of this class and has always worked in the manner set forth, so that after the splints are cut they are delivered in parallel rows and are separated row-wise. To obviate this difficulty, rods 27 are passed downward from the hopper 18 between the knives of the cutters 10, the rods lying in grooves 28 between the cutters and the lower ends of the rods being bent back slightly and secured to cross-bars 29. This arrangement prevents the splints from following the cutters and causes them to be deposited endwise in regular rows, as shown in Fig. 3. The splints of each row aline row-wise, but not in the opposite direction, as the drawings show.

When the splints are carried downward through the cutters 10, they are thrust endwise between the slats 31 of the dipping-frame 30, which frame, as illustrated, represents what is known as the ordinary "German" frame, except that the slats 31 are beveled or reduced on their upper edges to enable the splints to be easily guided between them; but other equivalent clamping-frames may be used in connection with my machine, if desired. The frame, as shown, has the parallel slats 31 held to slide on rods 32 at the two sides of the frame, and when the frame is full, with the splints sticking transversely through it, the slats 31 may be tight-

ened against the splints by the wedges 33, which are hung to slide on the rods 32 and which at the proper time are forced inward 70 by the cams 34, which are formed on the ends of the arms 35, and which will be again referred to below.

When the splints 39 are forced downward between the slats 31, the slats hold the two rows the correct distance apart for dipping, so that bad heads will not result; but the splints in each row are too near together. The mechanism described below separates the splints in the row and also provides for 80 heating them. As the splints go downward between the slats 31 they enter grooves 37 in the top of the guide-plate 36, which lies flatwise on the machine-frame at a point below the cutters 10, and as the splints of the two 85 rows do not aline the inner end of each groove 37 is curved, as shown clearly in Fig. 3, so that at each discharge of the cutters two splints are delivered into each groove 37, one being in the curved or inclined end and the other in the main part of the groove. It will be seen, however, that as the slats 31 are pushed forward the splints will also be carried forward, and after a short movement of the dipping-frame 30 the splints in the two 90 rows aline. To provide, however, for separating the splints sufficiently in the rows, the grooves 37 are made to diverge, as shown clearly in Fig. 1, until the part 40 of the guide-plate 36 is reached, at which point the 95 grooves 37 become parallel, and when the travel of the dipping-frame 30 has brought the splints to this point the divergence of the grooves will have separated them sufficiently, so that they will be in the proper position for 100 dipping. Just as the last end of the frame 30 reaches this parallel part 40 of the guide-plate the wedges 33 on opposite sides of the frame are pushed inward by the cam 34 and the splints are clamped in place. Beneath 110 this part 40 of the plate 36 are gas-jets 41, (see Fig. 4,) which heat the plate hot, and as the splints lie deep in the grooves 37 they are dried quickly and thoroughly not only at the ends, but throughout the greater part of their 115 length. Obviously this part 40 may be made of any necessary length, and when the dipping-frames are taken from it the splints are 120 ready to dip in paraffin preparatory to being dipped in a firing composition. It is evident that the plate 36 may be heated throughout its entire length, if desired. I have shown the plate 36 removable, it being supported on cross-bars 37^a. (See Fig. 2.)

It is obvious that the frames 30 may be fed into the machine from the front end and fed through the machine by many well-known devices; but I have illustrated what is a simple and very perfect means of accomplishing this result. The slats 31 are pushed forward 125 and at the same time separated to the necessary extent by horizontal gears 42 on opposite sides of the machine, which gears are carried on the vertical shafts 43, which are

mounted in suitable bearings, and each shaft is provided with a ratchet-wheel 44, which is engaged and turned by a pawl 45, each pawl being pivoted, as shown at 46, to the short 5 arm of a bell-crank 47, which is pivoted on the machine-frame, as shown at 48, and the bell-crank is connected by pitmen 49 with the eccentric-straps 25 already referred to. It will be seen, therefore, that when the eccentric-straps drop and carry down the plunger 22 they will also actuate the bell-crank 47, pawls 45, and ratchet-wheels 44, so that the shafts 43 and gear 42 will be turned sufficiently to advance the dipping-frames 30 the 10 distance of two slats, and consequently at every stroke of the plunger 22 the dipping-frame is advanced, so as to receive the rows of splints 39, which are cut by the cutters 10 on each descent of the plunger.

20 The above description shows that the machine is very complete and simple, and it will be clearly understood that any of the various well-known dipping-frames can be substituted for the German frame which I have seen fit to illustrate without affecting the principle of the invention and that the usual continuous carriers can be made to connect with the part 40, so as to receive the dipping-frames, if desired. I am well aware of the 25 fact that the dipping-frame, the cutting mechanism, and the stock-feed are not new, and, as before remarked, my invention lies chiefly in the arrangement of the guide and heating plate and the combination between this plate and a suitable cutting and clamping mechanism. It will be seen that the heating-plate referred to can be used for heating and drying splints without regard to the means for holding the splints, the only thing necessary 30 for this purpose being that some means be provided for holding the splints essentially perpendicular to the plate, and when used for drying simply the grooves in the plate may be parallel.

35 Having thus described my invention, what I claim as new, and desire to secure by Letters Patent, is—

40 1. A match-machine comprising a guide-plate having grooves therein, cutting mech-

anism adapted to deliver splints endwise into 50 the aforesaid grooves so that the splints stand perpendicular to the plate, and a dipping-frame movable between the cutting mechanism and the grooves so as to clamp the ends of the splints which project from the grooves. 55

2. In a match-machine, the combination of the grooved guide-plate, of splint-clamping mechanism movable over the face of the guide-plate, and splint-cutting mechanism arranged to discharge the cut splints directly into the 60 clamping means, and into the grooves of the guide-plate so that the splints are held essentially perpendicular to the plate.

3. In a match-machine, the combination with the guide-plate having diverging grooves 65 therein, said grooves at their inner ends being curved or inclined, of cutting mechanism arranged to deliver a row of splints in the inner or curved ends of the grooves and another row in the straight portion of the grooves, 70 and a holding or clamping device to grip the ends of the splints which project from the grooves.

4. In a match-machine, a combination with the guide-plate having diverging grooves 75 therein, of the holding-frame movable over the face of the grooves, means for delivering splints into the dipping-frame and grooves, and means as the wedges of the frame and the cams of the plate for locking the dipping- 80 frame, substantially as described.

5. In a match-machine, the combination with the guide-plate having grooves which diverge for a part of their length and then run parallel, of the dipping-frame movable over 85 the face of the guide-plate, the wedges of the frame to close it, and cams or abutments located opposite the junction of the diverging and parallel portions of the grooves to engage the wedges and lock the dipping-frame, sub- 90 stantially as described.

In testimony whereof I have signed my name to this specification in the presence of two subscribing witnesses.

WILLIAM F. HUTCHINSON.
